UNITED STATES PATENT OFFICE.

GEORGE H. WILLARD, OF HOPEDALE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed December 27, 1924. Serial No. 758,442.

To all whom it may concern:

Be it known that I, GEORGE H. WILLARD, a citizen of the United States, and a resident of Hopedale, in the county of Worcester and State of Massachusetts, have invented an Improvement in Feeler Mechanisms for Looms, of which the following description, in connection with the accompanying drawings, is a specification, like characters on the drawings representing like parts.

This invention relates to feeler mechanisms for looms and more particularly to feeler mechanisms of the intermittent type, wherein the feeler has periods of activity and periods of inactivity during weaving. In feeler mechanisms of the intermittent type the feeler is ordinarily held in an inoperative position during its periods of inactivity and is released at intervals that it may move rearwardly to its feeling position, and perform its feeling function during its periods of activity. The recurring contact of the feeler with the filling during feeler activity is objectionable, especially where the feeler receives upon it the full impact of the filling as the lay beats up or as the feeler itself moves backwardly to its full feeling position, and since the feeler only performs its functions to effect the change in loom operation at a critical period or when the filling is substantially exhausted on a detecting beat, even these recurrent contacts of the feeler with the filling as above outlined during the activity of the feeler become objectionable so long as a working supply of filling is present in the shuttle.

An important feature of the present invention therefore consists in means for releasing the feeler to its period of activity when the lay is at or is near front position, and in case the feeler at such times detects a working supply of filling in the shuttle it thereupon at once places the feeler in its active position. In accordance with the present invention, the feeler is released to the performance of its feeling function at intervals as the lay nears front position, so that the feeler contacts lightly with the filling when the lay is front, and should the feeler at such times detect a working supply of filling in the shuttle, it is returned to its period of inactivity at once without movement to its rearward feeling position, but should the feeler detect a near approach

to filling exhaustion, it will remain in its active position to call for a change in loom operation when the filling is substantially exhausted.

The invention and novel features and new combination of parts will best be made clear from the following description and the accompanying drawings of one good form thereof.

In the drawings:

Fig. 1 is a perspective view at the feeler side of the loom with some of the loom parts omitted, and showing more particularly features of the present invention;

Fig. 2 is a plan view on an enlarged scale of a feeler mechanism containing the present invention, some of the parts being shown in section;

Fig. 3 is an enlarged front elevation of the means for holding the feeler in a frontward inoperative position during its periods of inactivity and freeing it at intervals;

Fig. 4 is a section on the line 4—4 of Fig. 3; and

Fig. 5 is a side view of the feeler mechanism, some of the parts being broken away to show the parts beyond.

The invention will hereinafter be described in connection with a filling replenishing loom, but the details of the replenishing mechanism are not herein shown because they form no essential part of the present invention. The feeler is shown in the present instance as that of the inclined side swipe type, but it is to be understood that other forms of feelers may be advantageously employed in connection with the present invention.

The loom frame 1 may be of usual construction and has mounted at the front thereof the transverse or rock shaft 2, as usual, which is mounted in bearings 3, one at each side of the room, and extending upwardly from the rock shaft is an arm 4 having pivoted at 5 a rearwardly extending actuator 6. Pivoted connected to the actuator 6 at 7 is the rearwardly extending finger 8, the rear end portion of which is adapted at times to be engaged by an operating member 9 which may be the cam follower or a part operating in connection therewith. The rearwardly extending arm 8 has a projection 10 which overlies the arm 11 of a bell crank lever pivoted at 12 to a support 13 conveniently secured to the ship-

per stand 14 in the present instance at 15. The other arm 16 of the bell crank lever is connected with a transmitter 17, one end of which is connected to a slide 18 mounted 5 in guideways 19 at the rear of the feeler stand 20. The feeler stand may be associated with the loom frame or shipper stand or other support by means of a bolt 21 which passes through a slot 22 formed in the side 10 of the feeler stand.

The feeler 23 is shown as provided with a toothed end portion 24 for engagement with a surface within the shuttle, and the feeler stem 25 extends frontwardly through 15 a bearing 26 and has an end portion 27 extending at an angle to the stem. The bearing 26 is notched at its front end portion, as indicated at 28, so that the feeler may partake of its sideswipe movement along the 20 filling carrier when filling is to be replenished, thereby operatively associating the rearwardly extending arm 8 with the operating member to effect replenishment of filling. 25 The feeler has a spring 29 which surrounds the stem of the feeler and bears at one end against the bearing 26 and at its other end rests against the bridge or collar 30 secured to the feeler, the construction 30 being such that the spring normally tends to move the feeler into its full rearward feeling position. The parts so far described, with the exception of the bearing 16, may be substantially as shown and described in 35 the patent to Edward S. Stimpson, No. 1,309,226, July 8, 1919.

In the present instance, the feeler stand 20 is provided with a cover plate 31 which may be conveniently secured to the feeler stand by screws or other fastening means 32.

Adjustably connected to the feeler stand is a bracket 33 which may be clamped in adjusted position by means of a bolt 34 which passes through a slot 35 of the bracket, and 45 in order to adjust the bracket and the parts carried thereby, towards and from the front of the loom, an adjusting screw 36 is provided which is threaded into the feeler stand.

50 In the present instance, the bracket 33 has a laterally extending arm 37 which affords a convenient support for the means which holds the feeler in its frontward inoperative position during its periods of inactivity. 55 Such means is herein shown as a detent 38 which is pivotally supported by the laterally extending arm 37 and is normally under the influence of a spring tending to move the detent into its feeler holding position.

60 As shown, the detent 38 is secured to a small rock shaft 39 which is mounted in a bearing 40 extending laterally from the supporting bracket 37. The shaft 39 has secured at one end thereof, as shown, a lug 41

to which one end of a spring 42 is secured, 65 the other end of the spring being secured at 43 to the bracket 37, the construction being such that the spring 42 normally tends to move the detent into holding engagement with the feeler that the latter may be retained in its frontwardly inactive position. 70

The end portion 44 of the detent is formed with an inclined or wedge surface 45 which is adapted to engage and ride over the end portion 27 of the feeler stem to withdraw the feeler frontwardly as the detent is rocked upon its pivotal support. The opposite side of the head 44 of the detent has the reversely inclined surface 46 which may be engaged by the projection 27 of the feeler stem when 80 the feeler is moved from the rearward feeling position to a frontward position, and after the projection 27 has passed the head 44 of the detent, the reversely inclined surface 46 of the detent will drop behind the 85 projection 27 and through the spring 42 cause the feeler to be withdrawn further frontwardly beyond the reach of the filling on detecting beats.

It is desirable that suitable stops be provided for limiting the pivotal movement of the detent, and to this end the laterally extending arm 37 has a projection 48, Fig. 1, which may be formed as part of or be secured to the arm 37, and afford a rest for 95 the base portion 49 of the detent, when the latter is in its full feeler holding position.

The laterally extending arm 37 may also be provided with a stop 50 which overlies a projection 51 formed as part of or secured 100 to the detent.

In accordance with the present invention, the feeler is to be released from its holding means from time to time during weaving, and in the present instance means are provided in the form of a sheathed wire 52, Fig. 4, which extends into the lug or projection 48, the end of the sheathed wire 52 bearing upon the projection 51 extending from the detent, the construction being such that 110 should lengthwise movement be imparted to the wire 52, it will lift the detent upwardly to free the feeler, as indicated in Fig. 3.

Mounted in the guideway 53, which may be conveniently provided on the cover of the 115 feeler stand, is a bunter 54, the rear end portion 55 of which is adapted to engage a surface on the lay on each detecting beat. In the present instance the surface engaged by the bunter consists of the front wall of the 120 shuttle 56 when the latter is in the detecting box, and in the present instance the front wall of the shuttle box is provided with the usual opening 57 which registers with a similar opening 58 in the front wall of the 125 shuttle to permit the end of the feeler to enter the shuttle and feel for the filling.

The front portion of the bunter 54 is

provided with a block 59 from which projects a pin 60 which is engaged with the bifurcated end of an arm 61 extending from the sleeve 62 pivotally supported on the 5 feeder stand or cover plate thereof. The sleeve 62 is pivotally mounted upon a bolt 63 extending upwardly from the feeder stand or cover plate, and the sleeve is normally under the influence of a spring tendency to move the bunter 54 rearwardly. In the present instance of the invention, a spring 64 is mounted within the sleeve 62 and has one end secured at 65 to a stationary bolt 66 and the other end secured at 10 67 to the sleeve, the construction being such that the spring normally tends to rock the sleeve in a direction to carry the bunter 54 rearwardly. Secured to the sleeve 62 and projecting oppositely to the arm 61 is a 15 cam-carrying arm 68, Figs. 1 and 5, the under surface of which is inclined or cam-shaped, as at 69, to afford means for actuating a step-by-step device as the bunter is moved frontwardly by the on-coming lay 20 during a detecting beat.

Secured to the side of the feeler stand and extending downwardly therefrom is a plate or support 70, Figs. 2 and 5, which affords a convenient means for supporting 25 a part of the step-by-step device, comprising a ratchet wheel and its associated parts. In the present instance of the invention, the ratchet wheel 71 is mounted upon a shaft 72 extending outwardly from the plate 30 or support 70, and between a housing or cover 73 and the face of the ratchet wheel 71 is interposed a spring 74 for preventing too free movement of the ratchet wheel under the impulse of its operating means, as 35 will presently be described.

Loosely mounted on the shaft 72 is a rocker 75 from which extends a pawl-carrying arm 76, Figs. 1 and 5. Mounted on the arm 76 is a pawl 77 which is adapted to 40 engage a tooth of the ratchet wheel 71 and step it along as the rocker is rocked in one direction. Projecting from the rocker 75 is a second arm 78, Figs. 1 and 5; having a 45 projection 79 which is held in the path of movement of the cam surface 69 by means of a spring 80, Figs. 1 and 5, one end of which bears upon a lug 81 extending from the plate or support 70 and the other end of which bears against a projection 82 carried by the rocker 75, more clearly shown in Fig. 5. When the bunter is moved frontwardly by the on-coming lay during a detecting beat, the inclined surface 69 will ride rearwardly over the projection 79 and 50 effect a step movement of the ratchet wheel 71, and as the bunter returns to its idle rearward position, the pawl 77 will perform its idle stroke, the effect being that on each 55 frontward movement of the bunter the ratchet wheel will be stepped along one or

more teeth to rotate the ratchet wheel step by step.

Pivottally supported on the plate 70 at 83 is an arm 84, the free end portion of which normally rests upon an end of the sheathed 70 wire 52, as indicated in Fig. 5, and said arm is provided with a projection 85 normally held in the path of movement of a lug or trip 86 carried by the ratchet wheel. The engaging portions of the lugs 85 and 86 are 75 such that as the ratchet wheel is stepped along, as hereinbefore described, and the parts 85 and 86 are brought into cooperative relation, the knife-edge portion of the lug 86 will during the frontward movement of 80 the lay, depress the lever 84 and then pass out of engagement therewith on the same beat of the lay, the result being that the trip device will be actuated on a detecting beat of the lay to first trip the detent and 85 then free it on the same beat of the lay.

Since the ratchet wheel and trip device are actuated by the bunter as the lay moves to or approaches its front position, it follows that the feeler will be released from its holding means or detent when the lay is approaching or at front center, so that the feeler will engage the filling lightly. Should the feeler at this time detect a working supply of filling in the shuttle when the 90 lay is in or near its front center, the detent will drop rearwardly of the lateral projection 27 of the feeler stem, and prevent the feeler from going back with the lay. In other words, the trip device acts momentarily to trip the detent and then release it, so that it may at once go into action when the lay is approaching or near front center, and if at this time the feeler detects a working supply of filling in the shuttle, the detent will again drop into feeler holding position and prevent rearward movement of the feeler, so that during its period of activity when a working supply of filling is 95 in the shuttle, the feeler does not move to 100 its rearward feeling position.

As the filling is withdrawn from the shuttle during weaving, the diameter of the filling opposite the feeler will diminish until it will not be sufficient to meet the feeler when the lay is at or near front position unless the feeler itself moves rearwardly and consequently the feeler, when released by the detent, will move rearwardly to meet the filling, with the result that the end 27 of 115 the feeler will move rearwardly of the incline 45 of the detent as soon as the detent trips or frees the feeler, and the feeler will remain in action. During such active 120 period, which may be designated a near 125 approach to substantial exhaustion of filling, the usual teeth or end portion of the feeler will engage the filling on each detecting beat and hold the feeler from calling the change of filling until the amount of filling is no 130

longer sufficient to hold the feeler from movement along the bobbin, whereupon replenishment of filling will be effected.

The housing or cover plate 73 is supported upon the shaft 72, as hereinbefore stated, and in order to hold it in covering position, the plate 70 may be provided with a projection 87, Fig. 1, which may be extended into an opening 88 of the cover plate, but any suitable means may be employed for this purpose.

From the construction described it will be noted that the feeler has periods of activity and inactivity during weaving with the same supply of filling in the shuttle, and is released to its periods of activity when the lay is at or near front center, with the result that the feeler moves into light touching contact with the filling when a working supply is present in the shuttle, and since the detent is tripped and immediately released, the feeler is held from movement to its rearward position as the lay goes back on the same detecting beat on which it was released. Should, however, the feeler detect a near approach to exhaustion when released by the detent, it will move rearwardly to an extent dependent upon the amount of depleted filling in the shuttle as the detent moves again to its operative feeler-holding position, so that the detent will fail at this time to pass rearwardly of the projection 27 on the detent stem and the feeler will remain in operative or active position to call for a change of filling when that in the shuttle is substantially exhausted.

What is claimed is:

1. In a feeler mechanism for looms, the combination of a feeler, means for holding the feeler in an inoperative position, a trip to free the feeler from the holding means at intervals, as the lay approaches front center and permitting the holding means to again hold the feeler in inoperative position on the same detecting beat on which it was released should the feeler detect a working supply of filling in the shuttle on that beat.

2. In a feeler mechanism for looms, the combination of a feeler, means for holding the feeler in an inoperative position, means for freeing the feeler from the holding means as the lay approaches front center that the feeler may contact lightly with the filling and on the same detecting beat permitting the holding means to again hold the feeler in inoperative position should the feeler detect a working supply of filling in the shuttle on that beat that the feeler may not follow the backward movement of the lay.

3. In a feeler mechanism for looms, the combination of a feeler, feeler controlling means and operating mechanism therefor acting to hold the feeler in a frontward inoperative position and freeing the feeler at

intervals as the lay approaches front center on a detecting beat and upon detection of a working supply of filling in the shuttle on that beat continuing to hold the feeler from movement to rearward feeling position 70 as the lay goes back.

4. In a feeler mechanism for looms, the combination of a feeler, a device for holding the feeler in a frontward inoperative position, and controlling means for said device acting to free the feeler from the device at intervals as the lay approaches front center on a detecting beat and returning the holding device into holding relation with the feeler on the same detecting beat 80 should the feeler detect a working supply of filling in the shuttle on that beat.

5. In a feeler mechanism for looms, the combination of a feeler, a device for holding the feeler in an inoperative position, a trip for freeing the feeler from said device at intervals on a detecting beat and on the same detecting beat when the feeler detects a working supply of filling in the shuttle returning the device into holding relation 90 with the feeler that the latter may not move to rearward feeling position as the lay goes back.

6. In a feeler mechanism for looms, the combination of a feeler, a device for holding the feeler in an inoperative position, a trip for freeing the feeler from said device at intervals on a detecting beat and on the same detecting beat when the feeler detects a working supply of filling in the shuttle returning the device into holding relation with the feeler that the latter may not move to rearward feeling position as the lay goes back.

7. A feeler mechanism for looms, comprising, in combination, a feeler, a detent for holding the feeler in a frontward inoperative position, a trip for freeing the feeler from the detent at intervals as the lay approaches front center and permitting the detent to re-engage the feeler on the same detecting beat should the feeler detect a working supply of filling on that beat to prevent the feeler from moving rearwardly into feeling position as the lay goes back on the same beat.

8. A feeler mechanism for looms, comprising, in combination a feeler, a detent having a cam tooth to engage and hold the feeler in frontward inoperative position, a trip device for freeing the feeler at intervals only as the lay approaches front center that the feeler may lightly contact with the filling at or near front center and then passing out of freeing position that the detent may again engage the feeler before the lay goes back should the feeler have detected a working supply of filling in the shuttle.

9. In a feeler mechanism for looms, the

- combination of a feeler having periods of activity and inactivity with the same supply of filling in the shuttle, means cooperating with the feeler to hold it in a frontward inoperative position during its periods of inactivity, a trip for freeing the feeler, and means for operating the trip to free the feeler from its holding means as the lay approaches front centre that the feeler may contact lightly with the filling and on the same detecting beat permitting the feeler holding means to again hold the feeler in frontward position should the feeler detect a working amount of filling in the shuttle on that beat.
10. In a feeler mechanism for looms, the combination of a feeler having periods of activity and inactivity with the same supply of filling in the shuttle, means cooperating with the feeler to move it frontwardly and hold it in a frontward inoperative position during its periods of inactivity, a trip for freeing the feeler, a bunter, a rocking arm actuated by the bunter to operate the trip and effect release of the feeler only when the lay is at or near front centre that the feeler may lightly engage the filling and permit the feeler holding means to re-engage the feeler and hold it frontwardly should the feeler find a working supply of filling in the shuttle on the same detecting beat on which it was released.
11. In a feeler mechanism for looms, the combination of a feeler having periods of activity and inactivity with the same supply of filling in the shuttle, means including a detent pawl cooperating with the feeler to hold it in a frontward inoperative position during its periods of inactivity, a trip device to free the feeler from the holding means at intervals as the lay reaches front centre constructed and arranged to permit the holding means to again hold the feeler in inoperative position on the same detecting beat on which it was released should the feeler detect a working supply of filling in the shuttle on that beat and to permit the feeler to remain active in case rear approach to substantially exhaustion of filling is detected on that beat.
12. In a feeler mechanism for looms, the combination of a feeler having periods of activity and inactivity with the same supply of filling in the shuttle, a detent to hold the feeler in a frontward inoperative position during its periods of inactivity, a trip for the detent, a bunter for causing the trip to release the detent from the feeler only when the lay is near front center and permit the detent to again engage and hold the feeler on the same detecting beat to prevent rearward movement of the feeler when a working supply of filling is in the shuttle.

In testimony whereof, I have signed my name to this specification.

GEORGE H. WILLARD.
